SUCTION NOZZLE

Erik Oskar Helge Hansson, Stockholm, Sweden,
assignor to Electrolux Corporation, Dover, Del.,
a corporation of Delaware

Application November 25, 1936, Serial No. 112,624
In Germany November 26, 1935

1 Claim. (Cl. 285—96.8)

My invention relates to vacuum cleaners and more particularly to improved suction nozzles for use with vacuum cleaners.

One of the objects of my invention is to provide a nozzle including two parts which are angularly movable with respect to each other in order that the part including the suction mouthpiece may extend in practically any direction independently of the direction of the other part, 10 which is conveniently connected to the suction conduit.

A further object of my invention is the provision of a nozzle of this type which is of sturdy, simple and cheap construction and easily assembled.

Further objects and advantages of my invention will be apparent from the following description considered in connection with the accompanying drawings forming part of the specification and of which:

Fig. 1 is a view of a preferred embodiment of my invention in use in conjunction with a vacuum cleaner;

Fig. 2 is a view, chiefly in cross-section of a suction nozzle shown in Fig. 1;

Fig. 3 is a view of a nozzle found in Fig. 2 with the parts in a different relative position;

Figs. 4, 5 and 6 are detailed views of portions of the nozzle shown in Figs. 2 and 3;

Fig. 7 is a view, chiefly in cross-section of another embodiment of my invention;

Fig. 8 is a view of the nozzle shown in Fig. 7 with the parts in a different relative position, and

Fig. 9 is a cross-sectional view of a third embodiment of my invention.

Referring more particularly to Fig. 1, reference character 9 designates a vacuum cleaner unit to which is connected a hollow, rigid suction conduit 11 by means of a flexible hose 10. Sealed to the end of conduit 11 is the nozzle 12 which forms the subject matter of the present invention. Referring now more particularly to Figs. 2 through 6, the nozzle 12 includes two hollow members 13 and 14. Member 13 is formed at one end with a tapered bore 15 which is adapted to receive and engage the tapered end of conduit 11. The other end of member 13 is formed as a hemispherical portion 16, the circular edge of which lies in a plane oblique with respect to the axis of bore 15. Member 14 is formed with a similar hemispherical portion 17, the circular edge of which is likewise disposed in a plane oblique with respect to the axis. The edge of hemispherical portion 16 is formed with a shoulder 18 which fits within the circular open-

ing in hemispherical portion 17, thus preventing radial displacement of the two members. The edges of hemispherical portions 16 and 17 are retained in contact with each other by means of an arcuate resilient band 19 overlying the exteriors of the hemispherical portions and provided with projections 20 at either end which engage recesses 21 formed in the exterior of the hemispherical portions, as shown in Fig. 5. The recesses 21 are formed at opposite ends of a diameter which extends normal to the plane of the mating-edges of the hemispherical portions. The band 19 is also normal to this plane. Consequently, the hemispherical portions are relatively rotatable with respect to each other about an axis which coincides with the above mentioned diameter.

The resiliency of band 19 holds the two hemispherical portions together in substantially air-tight relationship and also permits easy assembly. To assemble the parts, the band 19 is sprung sufficiently for the projections 20 to pass over the outer surface of the hemispherical portions, and its resiliency causes it to contract and engage the projections 20 within the recesses 21.

The end of member 14 opposite from hemispherical portion 16 constitutes a nozzle opening 22. Brush bristles 23 surround this opening and are held within a metal retaining ring 24 which is disposed partly within an annular groove 25 formed in member 14. A rubber ring 26 is preferably placed around a shoulder 27 formed on member 14 and extends downwardly to conceal retaining member 24 and also serves to hold the retaining member in the recess 25. A hollow cylindrical member 28 is preferably disposed within the brush bristles 23 and serves to prevent the bristles from being drawn into the suction opening 22 by the inflowing air.

In order that the parts 13 and 14 may be retained in any desired position, the edge of one of the hemispherical portions is provided with one or more detents 29 adapted to be received in one of a series of recesses 30 formed in the edge of the other hemispherical portion, as is shown more particularly in Fig. 4. The resiliency of band 19 permits the slight separation of the two edges necessary for the detent to pass from one recess to the next. When the detent is received in a recess, band 19 maintains a substantially air-tight joint between the two edges.

Nozzle 12 may be applied directly to the end of hose 10 for use in dusting furniture and other objects that are within easy reach of the oper-

ator's hand. The parts 13 and 14 of the nozzle may be placed in any desired angular relation to each other. Fig. 1 shows the use of the nozzle for cleaning a ledge or moulding disposed above the operator's head. As here illustrated, the two parts of the nozzle are rotated to a position in which the angle between them is less than 90 degrees, thus making it possible for the part 14 to be in a substantially vertical position although the part 13 and the conduit 11 connected thereto extend downwardly from the nozzle.

In the embodiment shown in Figs. 7 and 8, the parts 13 and 14 are formed cylindrically with the edges of their mating-ends disposed in a plane oblique to their axis. An outwardly extending flange 35 is provided around the oblique edge of member 13, while a similar flange 36 is provided around the edge of member 14. These flanges are retained in contact with each other by means of a channel-shaped resilient ring 37 which is split, as is shown at 38 for the purpose of assembly. Means, such as the detent 29 and recess 30 shown in Fig. 4 may be employed to retain the members in any desired angular position.

In the embodiment shown in Fig. 9, the parts 13 and 14 are formed with hemispherical ends 16 and 17 in the same manner as described in connection with the embodiment illustrated in Figs. 1 through 6. Each hemispherical portion is provided with a groove 40 adjacent to the circular edge and a resilient channel-shaped ring 41, similar to ring 37 shown in Figs. 7 and 8, has its flanges engaging within these grooves. Ring 41 serves to retain the members in rotatable relation in the same manner as described in connection with the previous embodiment. The inner surfaces of the hemispherical members are

provided with ribs 42 which are disposed in plane parallel to the air passages formed in their respective members. The purpose of these ribs is to reduce swirling of the air as it passes through the hemispherical space formed by the two hemispherical portions. This swirling, under certain conditions, results in an undesirable noise. The presence of ribs 42 tend to cause the air to pass through the spherical space without swirling.

While I have shown and described three more or less specific embodiments of my invention, it is to be understood that this has been done for purposes of illustration only and that the scope of my invention is not to be limited thereby, but is to be determined by the appended claim viewed in the light of the prior art.

What I claim is:

In a suction nozzle including a first member having an air passage adapted to be connected to a source of suction, a second member having an air passage communicating with a nozzle opening, each of said members formed with a hemispherical end having a circular edge in a plane oblique with respect to the respective air passage, means to secure together said sections in coupled relation comprising an arcuate resilient band overlying said hemispherical ends and removably engaging the hemispheres at the opposite ends of the diameter normal to the plane of said edges, and means to retain said band in engagement with said hemispheres to resiliently hold said hemispherical ends together in substantial air-tight relation while permitting them to be pivoted relative to each other through a relatively wide angle, the resiliency of said band retaining the edges in abutting contact.

ERIK OSKAR HELGE HANSSON.
